UNITED STATES PATENT OFFICE.

ALBERT E. MAYNARD AND WILLIAM A. GUNNING, OF SOUTHBIDGE, MASSACHUSETTS, ASSIGNORS TO AMERICAN OPTICAL COMPANY, OF SOUTHBIDGE, MASSACHUSETTS, A VOLUNTARY ASSOCIATION OF MASSACHUSETTS.

TORIC-LAP FORMER.

Application filed June 5, 1920. Serial No. 386,760.

To all whom it may concern:

Be it known that we, ALBERT E. MAYNARD and WILLIAM A. GUNNING, citizens of the United States, residing at Southbridge, in the county of Worcester and State of Massachusetts, have invented certain new and useful Improvements in Toric-Lap Formers, of which the following is a specification.

This invention relates to improvements in lap forming machines and has particular reference to an improved machine for use in the construction of what is known as toric laps, that is to say, laps having different curves in opposite meridians, although it will be understood that the machine is also capable of use in connection with spherical or other similar forms of curves if desired.

The principal object of the present invention is the provision of a novel and improved construction of machine which shall be substantially automatic in operation, which will serve to accurately and positively generate the desired curve or combination of curves on the tool, and which shall be particularly desirable and efficient, in that it will serve to at one time produce a large number of tools of this peculiar and difficult to construct formation.

Other objects and advantages of our improved construction should be readily apparent by reference to the following specification taken in connection with the accompanying drawings and it will be understood that we may make any modifications in the specific details of construction shown and described within the scope of the appended claims without departing from or exceeding the spirit of the invention.

Figure I represents a front view of a machine embodying our improvements.

Figure II represents a side elevation thereof.

Figure III represents a sectional view as on the line III—III of Figure I.

Figure IV represents a front view of the machine arranged for the production of convex in place of concave surfaces, the principle of operation in both instances remaining the same.

In the drawings, the numeral 1 designates the main bed of our machine suitably supported and having journaled therein the shaft 2 of the lap bearing wheel 3, driven as by power applied to the pulley 4. This

wheel is of quite large diameter and is formed with a plurality of radially disposed grooves or guide-ways 5 slotted as at 6 for the studs 7 of the slides 8. These slides may have their in and out movement controlled as by the adjusting screw 9 provided with the head 10 for engagement with a suitable wrench, said screw working through the block 11 secured in the guide-way 5 as by the bolt or rivet 12. The studs 7, it is to be noted, are preferably threaded and clamped in position as by nuts 13 engaged on the rear face of the wheel 3 to aid the adjusting screw 9 in firmly and positively securing the slides 8 in desired radially adjusted position. It is to be noted that these slides project considerably from the face of the wheel and are each provided with the cone shaped studs 14 having the pins 15, these studs and pins being similar in configuration to the cone taper points of standard lens grinding machines, and being adapted to fit the sockets 16 of the lens grinding tools or laps 17, a single lap being mounted on each stud and the number of laps being operated upon by the machine at a single time being limited only by the strength of curve and the consequent limitation imposed as to the number of tools which may be grouped about the center of rotation, the greater the radius of curvature in the one meridian the larger the number of tools which may be simultaneously produced. For this reason it will be noted that there are a number of extra or supplemental slots 18 shown in the wheel 3 but not occupied or indicated as occupied by slides, in that view these supplemental slots or guide-ways being equipped only when tools of larger radius permitting their use are employed.

Secured upon the frame 1 for cooperation with the tools or laps, is a guide 19 having mounted thereon the slide 20 bearing a rotatable table portion or turret 21 having a worm gear 22 adapted to be driven at a slow rate of speed, as by the worm 23 on the shaft 24 which is slidable through the bevel gear 25 keyed thereon to transmit rotary movement to the shaft from the bevel gear 26 on the driven shaft 27, which in turn is coupled with a suitable source of power for applying slow rotary movement to the table 21. This table has adjustably secured thereon a tool holder 28 bearing a cutting tool 29 which

may be extended outwardly from the point 30 about which the table turns to any reasonable limit. In the operation of our improved machine a plurality of slides 8 are secured 5 equal distances from the center of rotation or axis of the shaft 2, and have mounted thereon the lens laps 17 which are rotated about the axis of the shaft 2. The slides are always supposed to be given an equal amount 10 of in and out adjustment, or in other words all are held an equal distance from the center or axis but this distance may be varied as desired according to the curve it is desired to produce in the central meridian parallel to 15 the face of the wheel 3.

The slides and laps to be shaped having been adjusted in the proper position or the length of radius of the curve to be produced from the axis of rotation, the tool slide 20 20 is then laterally shifted on the slide 19 till the point of the tool will properly engage a lap as carried there-past by rotation of the wheel 3 so that the tool will remove the necessary amount of material from the face of 25 the lap to impart the desired shape to it. It will thus be seen that as the wheel 3 rotates with the wheel in contact therewith, the point of the tool being a radius length from the center of rotation of the lap surfaces, 30 will prescribe that curve upon said surfaces.

It has been mentioned, however, that it is intended with this machine to produce toric surfaces on the tools in place of plain spherical surfaces. To accomplish this, 35 therefore, before adjustment of the tool holder slide 20 the tool itself was first adjusted to bring its point the proper distance from the center 30 for the transverse curve of the various tools. In operation, then, the 40 tool is swung about the axis 30 through the action of its drive worm and shaft and applies a cross curve of this radius to the several laps as they are carried by the tool, while on account of the center about which 45 the laps themselves rotate in a direction at right angles to the rocking of the tool is produced the spherical surface with distance from the point of tool to the center of rotation. In this way a compound curve is produced 50 on the face of each of the several tools and a number of said tools are simultaneously produced each having identical surfaces.

While we have particularly illustrated 55 and described this mechanism in connection with the formation of concave surfaces, it will be understood that the same identical principles apply in the formation of convex surfaces, except that the slides 8 are inside

and the studs 16 project outward and bear 60 the lens grinding tools, while the cutting point of the tool is directed inward and the several distances are measured from the center to outer surface of the tool and from inside toward the innermost point of the 65 tool. This type of construction is illustrated and should be readily understood by reference to Figure IV, since the principles involved are the same in the machines shown in Figures I and IV and the parts all 70 operate or function in the same way.

We claim:

1. In a device of the character described, the combination with a rotatable work holding wheel having a plurality of guide ways 75 formed in one face thereof, of work holders having portions slidably in said guide ways, and having projecting tool receiving studs and means for locking the work holders in adjusted position in the guide ways. 80

2. In a device of the character described, the combination with a rotatable wheel having guide ways formed therein, of tool holders slidably mounted in the guide ways, shoe adjustment means for controlling the 85 movement of the tool holders on the wheel in the guide ways, and means for locking the holders in desired adjusted position.

3. In a device of the character described, the combination with a rotatable work holding wheel, of a cutting tool holder oscillatable in a plane at right angles to the face of the wheel, and positive means for progressively oscillating the cutting tool holder 90 in one direction, said means including a worm and worm gear, and means for continuously operating said gears.

4. In a device of the character described, the combination with a rotatable work holding wheel, of a cutting tool holder oscillatable in a plane at right angles to the face of the wheel, and positive means for progressively oscillating the cutting tool holder in one direction, said means including a 100 worm and worm gear, means for continuously operating said gears, said means including a telescoping shaft member whereby the cutting tool holder and associated parts may be transversely adjusted as respects the face of the wheel without interference with the positive drive thereof.

In testimony whereof we have affixed our signatures, in presence of two witnesses.

ALBERT E. MAYNARD.
WILLIAM A. GUNNING.
